COUPLER SUPPORTING AND CENTERING DEVICE

Martin P. Blomberg, Hinsdale, and John M. Smidl, Cicero, Ill., assignors to General Motors Corporation, Detroit, Mich., a corporation of Delaware

Application April 17, 1944, Serial No. 531,328

18 Claims. (Cl. 213—61)

This invention relates to couplers for railway cars, and more particularly to a device for resiliently supporting and centering such couplers. The regulations of the Interstate Commerce Commission require that couplers be removed for inspection at periodic intervals, and since the usual forms of supporting and centering devices interfere with the removal of the coupler or link, provided the tail end is larger than the shank of the coupler, they must be taken off or at least partially disassembled before the coupler can be taken out. This takes several hours time and therefore in addition to increasing the cost of the inspection operation, it results in the car being kept out of service longer than is desirable.

It is therefore an object of this invention to provide a coupler supporting and centering device which is so constructed that by merely removing two keys which normally hold the device in operative position wherein swinging movement of the coupler to either side is yieldingly resisted, the upper portion of the device may be swung downwardly to a position wherein it will permit removal or replacement of the coupler. Thus it takes only a few minutes time to perform this operation as compared with the several hours required with the conventional coupler supporting and centering devices.

Another object is to provide such a device which is so designed that the entire assembly may be easily and quickly removed from the car when it becomes necessary to perform any service operations thereon.

Other objects and advantages of the invention will be apparent upon reference to the following description and accompanying drawings, in which:

Fig. 1 is a vertical sectional view, taken approximately on the longitudinal center line of the locomotive, as indicated by the line 1—1 of Fig. 2, showing the coupler and draft gear mechanism and our improved means for supporting and centering the coupler;

Fig. 2 is a plan view of the structure shown in Fig. 1, with portions broken away to show them in section;

Fig. 3 is a transverse view showing the coupler supporting and centering mechanism partly in section and partly in elevation;

Fig. 4 is a sectional view, taken on the line 4—4 of Fig. 3;

Fig. 5 is a transverse view, somewhat similar to Fig. 3, but showing a modified form of our invention; and

Fig. 6 is a transverse view, similar to Figs. 3

and 5, but showing a still different form of the invention.

The reference numeral 10 indicates the under-frame of a railway car or locomotive, to the underside of which is secured a coupler housing 12. 14 is a coupler yoke which is supported in the housing by the following structure. An inner wedge member 16 has angularly inclined surfaces 18 and a curved surface 20 formed on it, the curved surface bearing against a matching curved surface 22 formed at the inner end of the yoke. As shown in Fig. 2, this wedge member has projections 24 extending at each side thereof, and these projections normally bear against shoulders 26 formed in the coupler housing to prevent movement of the inner wedge member relative to the housing in one direction. 28 is an outer wedge member having a curved surface 30 on it, which surface bears against a matching curved surface 32 formed in the yoke. The wedge member 28 has angularly inclined surfaces 34 formed on it, and projections 36 extending from each side of it normally bear against shoulders 38 provided in the coupler housing to prevent movement of the wedge member 28 in one direction relative to the housing.

Located between the inner and outer wedge members are assemblies comprised of blocks 40 of rubber or other resilient material which are vulcanized to metal plates 42 and 44, the plates 42 bearing against the inclined surfaces 18 on the inner wedge member and abutting against shoulders 46 formed thereon, while the plates 44 bear against the inclined surfaces 34 on the outer wedge member and abut against shoulders 48 provided thereon. As shown in Fig. 1, the yoke 14 is supported by members 50 which are secured to the coupler housing by bolts 52, the yoke being free to slide longitudinally on the members.

The yoke has three spaced arms 54 formed at its outer end, and between these arms fit a pair of arms 56 extending from the shank 58 of a coupler 60, the coupler being pivotally connected to the yoke by a pin 62 which fits within bushings 64 extending through the arms 54 and 56, the pin being insertable from the bottom and being held in position by a key 66 which passes through lugs 68 depending from the lowermost arm 54 on the yoke.

The coupler is supported and normally is held in central position by the following structure. 70 is a fall projecting downwardly from the coupler housing and having a flange 72 extending horizontally from its lower end. A pair of brackets 74 secured to the wall 70 by bolts 76 each have

a leg 78 extending outwardly therefrom, and each of these legs has a semi-circular recess formed in it. 80 is a carrier member consisting of a round tube which extends between the brackets, the ends of the tube fitting in the recesses in the legs 78 and being welded thereto around the edges of the recesses on both sides of the legs, as indicated in Fig. 3. Mounted upon the carrier member is a saddle 82 which is made up of a round sleeve 84 having spring seats 86 welded to each end thereof, each of said spring seats having an upstanding wall 88 and connecting side walls 89 formed thereon.

Located above the saddle is a support member 90 having a central horizontally extending portion 92, to which is secured a wear plate 94 on which the coupler shank 58 is adapted to rest, vertically extending portions 96 which lie close to the walls 88 on the saddle, and horizontally extending end portions 98 which serve as seats for the upper ends of a pair of compression springs 100 provided at each end of the saddle to resiliently support the member 90 thereon, the lower ends of the springs bearing against the seats 86 on the saddle. Side walls 102 extending downwardly from the end portions 98 bear against the walls 89 and serve as guides to keep the support member in proper position with respect to the saddle. Other side walls 104 extending across the central portion 92 have a strap 106 secured to them by bolts 108, the strap extending downwardly around the bottom of the sleeve 84 and normally bearing against the latter to limit the upward movement of the support member caused by the expanding action of the springs 100.

Wear plates 110 are welded to the support member to withstand the rubbing action caused by the movement of the coupler shank during operation, and as the latter swings transversely when rounding curves, it engages one of these wear plates, forcing the vertically extending portion 96 to which it is secured against the adjacent upstanding wall 88 of the saddle, thereby tending to cause the saddle to slide in that direction on the carrier member. Such movement is however, yieldingly resisted by the following structure.

As shown in Figs. 3 and 4, adjacent to each end of the saddle is a key 112 which extends through elongated slots 114 formed in both sides of the sleeve 84 and elongated slots 116 formed in both sides of the tube 80. The keys are held in position in the slots by head members 118 secured in one end of the keys and cotter pins 120 extending through the opposite end. Located within the tube 80 are two spring blocks 122, each provided with a transversely extending groove 124 in which one of the keys is received to properly locate the blocks with respect to the keys. The ends of a pair of coil springs 126 and 128 bear against the blocks 122 and since the springs are of such lengths that when assembled within the tube they are placed under substantial initial compression, they serve to hold the blocks firmly against the keys, thus tending to move the latter outwardly in the slots 114 and 116. As shown in Fig. 4, while the inner ends of these slots are in line with each other, the slot 116 is slightly longer than the slot 114, so that while the keys are held against the outer end of the slot 114 by the action of the springs, they will not be quite in contact with the ends of the slots 116, since before they reach that position, the blocks 122 seat against the inner ends of ferrules 130 which form stops and which are slidably supported inside of the tube 80. The outer ends of these ferrules abut

against end walls 132 which are formed as a part of the coupler housing structure, the ferrules being forced outwardly against the end walls by the springs. The lower ends of the walls 132 extend inwardly as at 135 under the flange 72 where the lower ends of the brackets 74 rest on the flange, to assist in supporting the load imposed by the coupler. Slots 133 are formed in each side of the ferrules 130, and the keys extend through these slots, the keys being held against the ends of the slots by the blocks 122. 134 are circular plates welded inside of the ferrules adjacent the inner ends thereof to reinforce the latter.

When the coupler is swung to one side, as when the vehicle is rounding a curve, the shank 58 engages the wear plate 110 on that side of the support member and moves the latter in that direction so that it bears against the upstanding wall 88 on the saddle, thereby tending to slide the latter in that direction on the carrier member, but since the key 112 on the opposite side is in engagement with the outer ends of the slots 114 on that side of the sleeve 84, sliding movement of the latter causes that key to be moved in the same direction in the slots 116 and 133. The block 122 which bears against that key is likewise moved in that direction, thereby further compressing the springs 126 and 128 so that continually swinging movement of the coupler is yieldingly resisted, and the latter is moved back to central position by the action of the springs when the force which has caused it to swing sidewise is removed.

The springs 100 will permit vertical angling of the coupler in a downward direction, such movement being limited by the stops 93 on the support member engaging the tube 84, which results in the load being transferred to the carrier member, and from the latter through the brackets 74 to the flange 135 of the wall 132, which in effect is part of the framing structure. Vertical angling of the coupler in an upward direction is accomplished by simply lifting the shank with the support member 90 stationary, it being held by the strap 106.

Thus the coupler is normally held in central position, so that when two adjacent cars are to be coupled together, the coupler on each car will line up properly with that on the other, so that the two cars may be easily and quickly coupled together and so that no damage will occur to the couplers as might be the case if they were not in proper alignment with each other. It will be noted that a relatively slight amount of clearance is provided between the coupler shank 58 and the wear plates 110. This is to allow the coupler to be swung a little to either side of the center line to permit alignment with a coupler on an adjacent car when the cars to be coupled are standing on track with a slight degree of curvature, without encountering the resistance to swinging movement which is set up by the centering device.

It will be seen that only one of the keys 112 and one of the spring blocks 122 are moved transversely in the carrier member at a time. When the key and block at one side are being moved by the sliding action of the saddle, the key and block at the other side are stationary, the block at the latter side bearing against the inner end of the ferrule 130 on that side and serving as a stationary seat for the springs 126 and 128 which are being further compressed by the movement of the first key and block toward the second. When the coupler is swung to the other side, the

action is reversed so that the key and block which were stationary in the first instance become the moving ones, while the other key and block remain stationary. Thus it will be seen that by arranging the springs so that they may be compressed from either end to build up resistance to swinging movement of the coupler in either direction, it is only necessary to provide a single set of springs to return the coupler to central position from either side.

The regulations of the Interstate Commerce Commission require that the coupler be removed at certain intervals for inspection. To facilitate such removal, our improved construction has been designed so that the keys 112 may be removed by taking out the cotter pins 120 and driving the keys out of the slots 114, 116 and 133, whereupon the saddle 82 and the supporting member 90 may be swung outwardly or inwardly and downwardly as a unit relative to the carrier member, to the position shown in dot-and-dash lines in Fig. 1, which is approximately 120 degrees removed from its normal position. Such swinging movement is made possible because of the fact that the sleeve 84 which forms the base of the saddle is round and fits over the round tube which forms the carrier member. When the saddle and supporting member have been swung down to this position, they are out of the way so that ample space is provided through which the coupler or link may be withdrawn, after the pin 62 has been removed. Suitable openings may be provided in the sleeve 84 and the carrier member into which the keys may be inserted to positively hold the saddle and supporting member assembly in their lowered position so that they will not rotate on the tube when the coupler is being removed or installed.

Means are also provided to facilitate the removal of the entire assembly of the support member and saddle mounted upon the carrier member. Such means consists of a pair of holes 136 and 138 formed in each end of the carrier member 80 and in each ferrule 130. As best shown in Fig. 3, these holes are normally not in alignment with each other, the hole 138 in the ferrule being spaced somewhat further from the center than the hole 136 in the carrier, in order that a pry bar inserted in the two holes and pulled so that it tends to move the hole 138 into alignment with the hole 136 will serve to slide the ferrule inwardly in the tube a slight amount so that the outer end of the ferrule will be out of contact with the end wall 132, whereupon after removal of the bolts 76 the entire assembly may be withdrawn. Since at this time if the keys 112 were not in position in the slots, the expanding action of the springs would tend to force the ferrules out of place in the carrier member, a pin 140 is welded in each ferrule, and one end of these pins projects outwardly through the ferrule into elongated slots 142 formed in the carrier member. The length of the slots 142 is such that normal movement of the ferrules in the carrier member is not interfered with, but when the entire assembly is removed, outward movement of the ferrules in the carrier member is limited by the pins coming into contact with the outer ends of the slots 142. Thus the assembly is held together for convenience in handling it when it is being installed or removed.

As shown in Fig. 3, the ferrules 130 are cut away at the bottom as at 144 and holes 146 and 148 are provided in the carrier member and sleeve respectively in alignment therewith, to permit any water which may collect in the in-

terior of the carrier member to drain away. Fittings 150 are provided through which lubricant may be forced through suitable passages (not shown) to points between the sleeve 84 and the carrier member to reduce the friction therebetween.

The form of the invention shown in Fig. 5 is substantially like that previously described, with some minor variations. The same numerals are therefore used to refer to similar parts. One of the differences is that whereas the previously described device is intended to support and center a coupler, which has a relatively wide shank resting on and engaging the device, the one shown in Fig. 5 is intended for use where draft links are employed to connect two cars together instead of couplers. Draft links are commonly narrower in width than the shanks of couplers, so in order to have the centering device function properly in connection with a draft link such as shown at 158 in Fig. 5, filler members 160 are welded to the inner faces of the support member 90, and wear plates 162 are welded to these filler members.

Also provision has been made in the structure shown in Fig. 5 to support the air brake and signal pipes on the centering device so that they will swing with the latter when rounding curves so that no undue strain will be placed upon them. To accomplish this, a bracket 164 is welded to the sleeve 84 and the side walls 89 on the saddle. This bracket extends upwardly and outwardly at an angle, and has secured to it by U-bolts 166 the air brake pipe 168 and the signal pipe 170. The downwardly projecting portion 172 of the coupler housing on which the centering device is supported is curved outwardly as at 174 to provide clearance for the bracket and pipes when they swing with the coupler to the positions indicated by the dot-and-dash lines. 176 are lugs provided on each side of the housing to engage the coupler shank to limit the sidewise swinging movement of the latter, so that the portion 172 of the coupler housing need only be made strong enough to take the end thrust load of the springs 126 and 128, it not being required to take impacts or overloads since these are taken by the lug 176. The operation of the structure shown in Fig. 5 is the same as that previously described.

In the form of the invention shown in Fig. 6, the support member 180 is directly connected to or is formed as an integral part of the saddle 182, there being no springs between the two. This form of supporting and centering device is suitable for use with the type of coupler which has a relatively large amount of slack in the knuckle and which has no provision for holding two adjacent couplers in line with each other vertically. When such couplers are used, it is not necessary to support them resiliently, but instead a solid support such as is shown in Fig. 6 may be used. The carrier member 80 is supported at each end on portions 184 which extend downwardly from the coupler housing. The structure shown in Fig. 6 functions in the same manner as those previously described insofar as the features of centering the coupler and of being rotatable downwardly about the carrier member when the keys 112 are removed, to permit removal or replacement of the coupler.

While we have shown and described specific embodiments of our invention, it will be understood that various changes in the details of construction and operation may be made without departing from the spirit and scope of the appended claims.

We claim:

1. In a coupler supporting and centering device, the combination of a carrier member, a saddle slidably and rotatably mounted on said carrier member, and means connecting said saddle to said carrier member to normally prevent rotative movement relative thereto, said means being removable to allow said saddle and support member to be swung downwardly about said carrier member to permit withdrawal of the coupler.

2. In a coupler supporting and centering device, the combination of a carrier member, a saddle slidably and rotatably mounted on said carrier member, a support member resiliently carried by said saddle and adapted to support a coupler, and means connecting said saddle to said carrier member to normally prevent rotative movement relative thereto, said means being removable to allow said saddle and support member to be swung downwardly about said carrier member to permit withdrawal of the coupler.

3. In a coupler supporting and centering device, the combination of a carrier member, a saddle slidably and rotatably mounted on said carrier member, a support member resiliently carried by said saddle and adapted to support a coupler, means serving to yieldingly resist sliding movement of the saddle relative to said carrier member, and other means adapted to prevent rotative movement of the saddle relative to said carrier member.

4. In a coupler supporting and centering device, the combination of a carrier member, a saddle slidably and rotatably mounted on said carrier member, a support member resiliently carried by said saddle and adapted to support a coupler, a spring serving to resist sliding movement of the saddle relative to said carrier member, and removable means adapted to prevent rotative movement of the saddle relative to said carrier member.

5. In a coupler supporting and centering device, the combination of a carrier member, a saddle slidably and rotatably mounted on said carrier member, a support member resiliently carried by said saddle and adapted to support a coupler, a spring adapted to resist sliding movement of the saddle relative to said carrier member, and a pair of keys connecting said saddle to said carrier member and serving to prevent rotative movement of the saddle relative to said carrier member.

6. In a coupler supporting and centering device, the combination of a carrier member, a saddle slidably and rotatably mounted on said carrier member, a support member resiliently carried by said saddle and adapted to support a coupler, a spring located within the carrier member, and means connecting said saddle to said carrier member, said means cooperating with said spring whereby the latter will yieldingly resist sliding movement of the saddle relative to the carrier member.

7. In a coupler supporting and centering device, the combination of a carrier member, a saddle slidably and rotatably mounted on said carrier member, a support member resiliently carried by said saddle and adapted to support a coupler, a spring located within the carrier member, and removable means connecting said saddle to said carrier member, said means serving to prevent rotation of the saddle relative to the carrier member and being adapted to cooperate with said spring in such manner that the latter will serve to yieldingly resist sliding movement of the saddle relative to the carrier member.

8. In a coupler supporting and centering device, the combination of a carrier member, a saddle slidably and rotatably mounted on said carrier member, a support member resiliently carried by said saddle and adapted to support a coupler, a spring located within the carrier member, and a pair of keys connecting said saddle to said carrier member, said keys being so arranged that sliding movement of the saddle relative to the carrier will serve to compress said spring whereby such movement will be yieldingly resisted.

9. In a coupler supporting and centering device, the combination of a carrier member, a saddle slidably and rotatably mounted on said carrier member, a support member resiliently carried by said saddle and adapted to support a coupler, a spring located within the carrier member, and a pair of removable keys connecting said saddle to said carrier member, said keys serving to prevent rotation of the saddle relative to the carrier member and being adapted to cooperate with said spring in such manner that the latter will serve to yieldingly resist sliding movement of the saddle relative to said carrier member.

10. In a coupler supporting and centering device, the combination of a carrier member, a saddle slidably and rotatably mounted on said carrier member, a support member resiliently carried by said saddle and adapted to support a coupler, and a pair of removable keys extending through said saddle and carrier member and serving to connect the two together, said keys permitting sliding movement of the saddle relative to the carrier member but preventing rotative movement relative thereto.

11. In a coupler supporting and centering device, the combination of a carrier member, a saddle slidably and rotatably mounted on said carrier member, a support member resiliently carried by said saddle and adapted to support a coupler, a spring located within the carrier member, and a pair of keys extending through said saddle and carrier member and serving to connect the two together, said keys serving to prevent rotation of the saddle relative to the carrier member and being adapted to cooperate with said spring in such manner that the latter will serve to yieldingly resist sliding movement of the saddle relative to said carrier member.

12. In a coupler supporting and centering device, the combination of a carrier member, a saddle slidably and rotatably mounted on said carrier member, a support member resiliently carried by said saddle and adapted to support a coupler, said carrier member and said saddle each having aligned slots formed in opposite side walls thereof, and a pair of keys extending through said slots, said keys serving to prevent rotative movement of the saddle relative to the carrier member and sliding in said slots when the saddle slides on the carrier member.

13. In a coupler supporting and centering device, the combination of a carrier member, a saddle slidably and rotatably mounted on said carrier member, a support member resiliently carried by said saddle and adapted to support a coupler, a spring located within said carrier member, said carrier member and said saddle each having aligned slots formed in opposite side walls thereof, a pair of keys extending through said slots, said keys serving to prevent rotative movement of the saddle relative to the carrier member and being adapted to slide in said slots and to cause said

spring to be compressed when the saddle slides on the carrier member.

14. In a coupler supporting and centering device, the combination of a carrier member, a saddle slidably and rotatably mounted on said carrier member, a support member resiliently carried by said saddle and adapted to support a coupler, a spring located within the carrier member, a block bearing against each end of said spring, and means serving to connect said saddle to said carrier member, said means serving to prevent rotation of the saddle relative to said carrier member and being adapted to engage one of said blocks when the saddle slides on the carrier and thereby cause said spring to be compressed to yieldingly resist such sliding movement.

15. In a coupler supporting and centering device, the combination of a carrier member, a saddle slidably and rotatably mounted on said carrier member, a support member resiliently carried by said saddle and adapted to support a coupler, a spring located within the carrier member, a block bearing against each end of said spring, a stop located within the carrier member at each end thereof, said blocks seating against said stops, and means extending through said carrier member and saddle to prevent rotative movement of the saddle relative to the carrier member, said means being adapted when the saddle slides relative to the carrier member to move one of said blocks in a direction which will cause said spring to be compressed to resist such sliding movement.

16. In a coupler supporting and centering device, the combination of a carrier member, a saddle slidably and rotatably mounted on said carrier member, a support member resiliently carried by said saddle and adapted to support a coupler, a spring located within the carrier member, a block bearing against each end of said spring, a stop located within the carrier member at each end thereof, said blocks seating against said stops, said carrier member and saddle each having aligned slots formed in opposite side walls thereof adjacent each of said blocks, and a key extending through said slots between each of said blocks and the stop it is seated against, whereby when the saddle slides relative to the carrier member, the key at one end will move the adjacent block away from its stop and cause the spring to be compressed to resist such sliding movement.

17. In a coupler supporting and centering device, the combination of a carrier member consisting of an annular tube supported at its ends on the coupler housing, a saddle including an annular sleeve mounted on said tube, a support member resiliently carried on said saddle and adapted to support a coupler, a spring located within the carrier member, a block bearing against each end of said spring, a ferrule located within the carrier member at each end thereof, said blocks seating against said ferrules, a pair of keys extending through said carrier member and saddle to prevent rotative movement of the saddle relative to the carrier member, said keys being adapted when the saddle slides relative to the carrier member to move one of said blocks in a direction which will cause said spring to be compressed to resist such sliding movement, and means adapted to limit outward movement of the ferrules in the carrier member when the latter is removed from its supports on the coupler housing.

18. In a coupler supporting and centering device, the combination of a carrier member consisting of an annular tube supported at its ends on the coupler housing, a saddle including an annular sleeve mounted on said tube, a support member resiliently carried on said saddle and adapted to support a coupler, a spring located within the carrier member, a block bearing against each end of said spring, a ferrule located within the carrier member at each end thereof, said blocks seating against said ferrules, a pair of keys extending through said carrier member and saddle to prevent rotative movement of the saddle relative to the carrier member, said keys being adapted when the saddle slides relative to the carrier member to move one of said blocks in a direction which will cause said spring to be compressed to resist such sliding movement, and means adapted to move said ferrules inwardly in said carrier member against the compression of said spring so that they will be out of contact with the coupler housing to permit removal of the carrier member from its supports in the coupler housing.

MARTIN P. BLOMBERG.
JOHN M. SMIDL.
